(57) **CLAIM**

The ornamental design for a drawer organizer, as shown and described.

DESCRIPTION

FIG. 1 is a front, right, top perspective view of a drawer organizer, showing my new design in a first condition of use; FIG. 2 is a rear, left, bottom, perspective view thereof; FIG. 3 is a front elevation view thereof; FIG. 4 is a rear elevation view thereof; FIG. 5 is a left side view of thereof; FIG. 6 is a right side view thereof; FIG. 7 is a top plan view thereof; FIG. 8 is a bottom plan view thereof; FIG. 9 is an enlarged view of detail 9 in FIG. 2; FIG. 10 is an enlarged view of detail 10 in FIG. 2; FIG. 11 is a front, right, top perspective view of the drawer organizer, shown in a second condition of use; and, FIG. 12 is a rear, left, bottom, perspective view thereof. The dashed broken lines in the figures illustrate portions of the drawer organizer which form no part of the claimed design. The dash-dot-dash broken lines are for notating enlarged views and form no part of the claimed design.

1 Claim, 12 Drawing Sheets
